DESIGN FOR A COMBINED CIGARETTE CASE AND LIGHTER

Richard F. Landwehr, Laurelton, N. Y., assignor
to Sagamor Metal Goods Corporation, New
York, N. Y., a corporation of New York

Application April 5, 1941, Serial No. 100,167

Term of patent 7 years

To all whom it may concern:

Be it known that I, Richard F. Landwehr, a citizen of the United States and a resident of Laurelton, in the county of Queens, State of New York, have invented a new, original, and ornamental Design for a Combined Cigarette Case and Lighter, of which the following is a specification, reference being had to the accompanying drawing, forming part thereof.

Figure 1 of the drawing is an isometric view of

a combined cigarette case and lighter, showing my new design, with both the case and the lighter closed.

Figure 2 is a side view of the same, with the case closed and the lighter open.

I claim:

The ornamental design for a combined cigarette case and lighter, substantially as shown.

RICHARD F. LANDWEHR.
